United States Patent Office

Des. 223,257
Patented Apr. 4, 1972

223,257

DECORATIVE NOVELTY OR THE LIKE

Hugh N. Pace, 4629 Poole Road,
Raleigh, N.C. 27610

Filed May 4, 1970, Ser. No. 22,797

Term of patent 14 years

Int. Cl. D11—02

U.S. Cl. D29—23

Fig 1

Fig 4

FIG. 1 is a front elevational view of a decorative novelty or the like, showing my new design;

FIG. 2 is a side elevational view thereof;

FIG. 3 is a rear elevational view; and

FIG. 4 is a bottom plan view.

I claim:

The ornamental design for a decorative novelty or the like, as shown.
